UNITED STATES PATENT OFFICE

HENRY F. GEISE, OF WHITES, WASHINGTON

ARTIFICIAL HAND

Application filed August 19, 1930. Serial No. 476,368.

This invention relates to the class of artificial body members and pertains particularly to an artificial hand, being an improvement upon the artificial hand disclosed in my Patent No. 1,557,355 of October 13, 1925.

The primary object of the present invention is to provide an improved artificial hand wherein certain adjustments necessary to the proper operation of the hand through coacting movements of the upper arm and forearm, may be made easily and quickly thus increasing the ease with which the actuation of the artificial hand may be accomplished.

In my former application above referred to a pair of coacting members forming the artificial hand are actuated relative to one another as a result of relative movements between the upper arm and forearm, through the medium of an actuating lever. This actuating lever has one end disposed adjacent the elbow of the wearer and this end must be shifted to selected positions in order to accomplish certain movements of the two elements constituting the hand. Since the mechanism which actuates the hand is enclosed within the wearer's sleeve it will be readily seen that some difficulty must be experienced in adjusting the inner end of the actuating lever. With the present invention the difficulty encountered in adjusting the actuating lever of the hand is overcome through certain novel rearrangements of the parts and changes in the construction of the hand actuating lever.

A further object of the present invention is to provide an improved hand construction which is adapted to perform a greater variety of functions than hand structures of the character heretofore devised.

The invention will be best understood from a consideration of the following detailed description taken in connection with the accompanying drawings forming part of this specification, with the understanding, however, that the invention is not confined to any strict conformity with the showing of the drawings but may be changed or modified so long as such changes or modifications mark no material departure from the salient features of

the invention as expressed in the appended claims.

In the drawings:

Figure 1 is a view in side elevation of the improved artificial hand and operating mechanism therefor embodying the present invention.

Figure 2 is a view in top plan of the same.

Figure 3 is a sectional view taken on the line 3—3 of Figure 1.

Figure 4 is a horizontal sectional view taken on the line 4—4 of Figure 1.

Figure 5 is a detailed sectional view through the gripping elements of the hand.

Figure 6 is a detailed view in plan of the gripping elements of the hand showing certain adjustments which may be made thereto.

Figure 7 is a sectional view taken on the line 7—7 of Figure 5.

Figure 8 is a sectional view taken on the line 8—8 of Figure 1.

Figure 9 is a sectional view taken on the line 9—9 of Figure 5.

Referring more particularly to the drawings the numerals 1 and 2 indicate respectively the upper arm and forearm encasing sleeves of the present device. The upper arm encasing sleeve 1 has disposed at opposite sides and longitudinally thereof the reinforcing bars 3 and 4, the lower ends of which extend beyond the lower ends of the sleeve as shown and have pivotal connection as at 5 with the reinforcing bars 6 and 7 which extend longitudinally of the forearm encasing sleeve, these latter bars being secured at their forward ends to the band 8 encircling the forward end of the sleeve 2.

The bars 3 and 4 adjacent their upper ends have attached thereto the usual rings 9 by means of which the body strap used with the artificial limb may be attached thereto. The bar 3 which is upon the outside of the device, assuming that the device shown is for attachment to a right arm, has secured thereto adjacent the upper end a plate 10 which has its rear edge extended beyond the supporting bar 3 and provided with a series of apertures 11.

Immediately below the plate 10 a short bar 12 is secured longitudinally of the bar

3 and is held in spaced relation thereto as shown in Figure 3, the lower end of this bar overlying the rear end of the forearm reinforcing bar 7 and being secured in place by the rivet 5 which pivots the two reinforcing bars 3 and 7 together.

The forearm reinforcing bar 7 is upon the outer side of the sleeve 2 and mounted thereon adjacent the rear end or the elbow of the 10 device is a bearing 13. At its forward end the bar 7 has formed integral therewith a laterally projecting ear 14 which has an aperture therethrough which is in alignment with the bearing 13.

15 Mounted longitudinally along the outer side of the bar 7 with one end supported in the bearing 13 and the other or forward end supported in and extending through the aperture in the ear 15, is a shaft 16, the rear 20 end of which has a collar 17 secured thereto which prevents its longitudinal movement in one direction through the bearing 13, movement in the opposite direction being prevented by the shoulder formed adjacent the 25 opposite end of the bearing where the shaft is reduced for extension through the bearing. This shaft 16 is cut away as indicated at 18 from a point forwardly of the bearing 13 to its forward end so that it is of 30 substantially semi-circular cross-section through the major portion of its length. At its forward end beyond the ear 14 the shaft 16 is curved slightly laterally as indicated at 19 and terminates in a bearing eye 20.

35 Slidably disposed longitudinally of the shaft 16 in the cut out portion thereof is a semi-cylindrical reciprocable shaft 21. The forward end of this shaft 21 also passes through the aperture of the ear 14 and extends forwardly thereof terminating in the bearing eye 22. The shaft 16 forwardly of the ear 14 has surrounding it and fixed to it a collar 23 which also surrounds the reciprocable shaft 21. This collar has formed 45 integral therewith the ear 24.

Surrounding both of the shafts 16 and 21 at a point between the bearing 13 and ear 14 is a collar 25 which is free to move along the shaft 16 but is held against movement on 50 the shaft 21 by the pins 26. This collar 25 carries two ears 27 and 28, the ear 27 extending upwardly and the ear 28 extending downwardly as shown in Figure 1. The ear 28 has attached thereto a hook 29 to which 55 is connected one end of a spring 30 which has its other or rear end attached to the pin 31 carried by the fixed bearing 13. It will thus be seen that this spring 30 tends to draw the collar 25 rearwardly and also the 60 reciprocable shaft 21 which is attached thereto. The ear 28 also carries, at a point below the hook 29, the pivot pin 32 which 65 is slidably and pivotally engaged in the slot 33 formed longitudinally and through the lower end of an oscillatable member 34.

This member 34 is disposed between the shafts 16 and 21 and the forearm reinforcing bar 7, and is pivotally secured intermediate its ends to the bar 7. The ear 27 carries adjacent its upper end and projecting from its outer face the headed pin 35 while the oscillatable member carries at its upper end the headed pin 36 which projects from its inner face.

Designed for selective engagement with the pins 35 and 36 is an operating lever 37 which is disposed above the shafts and longitudinally thereof and is pivotally mounted adjacent its rear end as at 38 between the bar 3 and the bar 12 which is disposed in offset relation thereto. The forward end of the lever 37 is slightly increased in width and this widened portion has formed in the lower edge thereof a series of notches 39 which are designed to receive the pins 35 or 36 as desired by the user. The rear end of the lever 37 is formed to provide the hook 40 to which is attached one end of a tension spring 41, the other end of this spring being attached by means of a suitable pin 42 to the plate 10, the pin being adapted for selective engagement in the apertures 11 and also being disposed between the plate 10 and the sleeve 1. Upon the forward face of the ear 14 there is mounted a ring 42' the periphery of which is provided with 50 transverse recesses 43.

At the forward ends of the shafts 16 and 21 there is positioned a pair of gripping members one of which, indicated generally by the numeral 44, may be termed a thumb while the other which is indicated generally by the numeral 45 may be termed a finger. As shown each of these members 44 and 45 is made up of two portions, the portions of the member 44 being indicated by the numerals 46 and 47 while the portions of the member 45 are indicated by the numerals 48 and 49. Each of the portions 46 and 48 is in the form of a U-shaped frame which is formed from a strip of relatively broad metal. Each leg of 105 each of the portions 46 and 48 is formed at its free end and at each longitudinal edge to provide hinge ears 50 and 51.

The hinge ears 51 of the two U-shaped frames 46 and 48 are disposed with the apertures formed therethrough in alignment with the hinge ear 22 of the reciprocable shaft 21 and are connected therewith by a suitable pivot pin 52. The hinge ears 50 of the portion 48 have connecting therebetween a pin 53 to 120 which is attached the adjacent ends of a pair of links 54, the other ends of which are attached as at 55 to the ear 24 carried upon the collar 23. The pin 55 which connects the links 54 with the ear 24 also carries a 125 finger 56 which, when the members 44 and 45 are swung apart, engages in one of the recesses in the periphery of the ring 42'. The ears 50 upon the portion 46 of the member 44 are pivotally connected by means of a 130

suitable pin 57 with the hinge eye 20 which forms the forward terminus of the shaft 16.

The outer portions 47 and 49 of the members 44 and 45 are also of substantially U-shaped design and are formed from a relatively broad strip of metal the same as the members 46 and 48. These outer portions 47 and 49 have the yokes thereof pivotally attached by the members 58 to the yokes of the adjacent portions 46 and 48 so that these outer portions may be rotated upon the inner portions, as shown in Figure 6. Suitable spacing bodies are disposed between the sides of the inner and outer portions of the gripping members as indicated by the numeral 59. These spacing bodies fill up substantially all of the space between the sides of these parts of the members with the exception of the portion 49 wherein the area lying between the sides thereof is left open so that the adjacent portion 47 may move thereinto.

As shown in Figure 5 the free ends of the outer portions 47 and 49 are curved so that they may be brought into opposed relation to permit one to move into the other as described or to hold a body between the opposed ends. When holding a body between the curved opposed ends the relative positions of the members will be as shown in Figures 1 and 5.

Each of the inner members 46 and 48 has pivotally secured to each side face a latching plate 60 which may be positioned to extend longitudinally of the member in which case it will overlie the joint between the inner and outer portions thereof and thus prevent the outer portion of the member from being turned. By swinging this plate around in one direction the outer portion of the member adjacent thereto may be turned to a position at right angles to that which it formerly assumed, as shown in Figure 6, after which the latching plate may be turned back to overlie the adjacent end of the turned outer member and thus hold it in the position in which it has been set. Each of the latching plates at its inner end is provided with a hook 61 which receives a pin 62 projecting from the side of the supporting member to limit the swinging movement of the latching plate.

From the foregoing description it will be readily apparent that when a device of the character herein described is in use no difficulty will be experienced by the user in lifting and adjusting the actuating lever 37 thereof as the free end of the lever is disposed adjacent the forward or wrist end of the forearm receiving sleeve.

It will also be readily seen that by engaging the pin 36 of the oscillatable bar 34 in one of the notches 39 of the operating lever when the upper arm encasing sleeve 1 is in the position shown, or in other words when the arm is bent, and then straightening out the

arm, the oscillatable member 34 will move the sleeve 25 forwardly and thus shift the reciprocable shaft 21 forwardly to cause separation of the thumb and finger members 44 and 45. At the same time the spring 30 will be placed under tension so that when the arm is again bent this spring will assist in returning the parts to the position in which they are shown in Figure 1. Should the arm of the user of the device be in the straightened out condition or partially straightened out and the lever have one of the notches 39 engaged with the pin 35 it will be seen that by bending the arm the same effect will be obtained, that is the shaft 21 will be shoved forwardly and cause the members 44 and 45 to separate. The spring 30 also serves to keep the members 44 and 45 in engaged relation when the lever 37 is out of engagement with the pins 35 and 36. Accidental disengagement of the lever 37 from either the pin 35 or the pin 36 is prevented by the spring 41 which acts to constantly urge the forward or free end of the lever downwardly.

Having thus described my invention, what I claim is:

1. In a device of the character described, an upper arm receiving sleeve and a forearm receiving sleeve, a pivotal connection between said sleeves, a member mounted for longitudinal reciprocation at one side of said forearm sleeve, a pair of members mounted at the forward end of said forearm sleeve, said members being adapted for relative movement for the engagement of a body therebetween, said first member when moved toward the rear of said sleeve effecting the bringing together of said pair of members, a lever permanently pivotally attached adjacent one end to said upper arm sleeve, means for detachably connecting the other end of said lever to said shiftable member whereby the latter will be shifted longitudinally upon bringing said sleeves into angular relation one with the other, for effecting relative movement of said pair of members, and a resilient control element having connection with said lever at its pivoted end and normally maintaining the connection of the other end with said shiftable member.

2. A device of the character described, comprising a sleeve designed to receive a handless forearm, an upper arm receiving sleeve pivotally connected with the forearm sleeve, a shaft mounted at the side of the forearm sleeve for movement longitudinally thereof, a pair of pivotally connected gripping elements mounted at the forward end of the forearm sleeve and having pivotal connection with said shaft whereby upon actuation of the shaft relative movement of the gripping members will be effected, an elongated member pivotally mounted intermediate its ends adjacent said shaft, pivotal connecting means between said shaft and one end of said last

mentioned member, a lever having pivotal connection at one end with said upper arm sleeve, and means for detachably connecting the other end of the lever with the other end of said pivotally mounted member.

3. A device of the character described, comprising a sleeve designed to receive a handless forearm, an upper arm receiving sleeve pivotally connected with the forearm sleeve, 10 a shaft mounted at the side of the forearm sleeve for movement longitudinally thereof, a pair of pivotally connected gripping elements mounted at the forward end of the forearm sleeve and having pivotal connection 15 with said shaft whereby upon actuation of the lever relative movement of the gripping members will be effected, an elongated member pivotally mounted intermediate its ends adjacent said shaft, pivotal connecting means 20 between said shaft and one end of said last mentioned member, a lever having pivotal connection at one end with said upper arm sleeve, means for detachably connecting the other end of the lever with the other end of 25 said pivotally mounted member, and resilient means normally acting to draw said shaft inwardly from the free end of the forearm sleeve to maintain said gripping members in closed relation.
4. In a device of the character described, a sleeve designed to receive a handless forearm, an upper arm receiving sleeve pivotally connected to the first mentioned sleeve, a shaft mounted adjacent the forearm sleeve for movement longitudinally thereof, a pair of 30 pivotally connected gripping members mounted at the forward end of the forearm sleeve and having connection with said shaft for actuation thereby, an ear carried by said shaft, and below the same, a bar disposed substantially transversely of the shaft and pivotally mounted intermediate its ends and further having sliding pivotal connection at its lower end with said ear, and a lever pivotally 35 attached at one end to said upper arm sleeve and adapted for selective engagement at its other end with the upper end of the pivoted bar.

5. In a device of the character described, 40 a sleeve designed to receive a handless forearm, an upper arm receiving sleeve pivotally connected to the first mentioned sleeve, a shaft mounted adjacent the forearm sleeve for movement longitudinally thereof, a pair of 45 pivotally connected gripping members mounted at the forward end of the forearm sleeve and having connection with said shaft for actuation thereby, an ear carried by said shaft, and below the same, a bar disposed 50 substantially transversely of the shaft and pivotally mounted intermediate its ends and further having sliding pivotal connection at its end with said lower ear, a lever pivotally 55 attached at one end to said upper arm sleeve and adapted for selective engagement at its 60

other end with the upper end of the pivoted bar, and resilient means normally tending to urge the free end of said lever in one direction to maintain connection between the lever and the engaged bar.

6. In a device of the character described, comprising a pair of sleeves, one being designed to receive a handless forearm and the other to receive an upper arm, frame bars extending longitudinally of opposite sides of each of said sleeves, pivotal connecting means between adjacent ends of said frame bars, a shaft mounted upon and extending longitudinally of a frame bar adjacent the forearm sleeve and having one end extended beyond the forward end thereof, said shaft being of substantially semi-circular cross-section from a point adjacent its inner end to its forward end, a reciprocable substantially semi-circular shaft mounted to slide upon the flat portion of the first mentioned shaft, a sleeve surrounding said shafts and having an ear, said sleeve being slidably upon the first mentioned shaft and secured against movement on the reciprocable shaft, a bar pivotally mounted intermediate its ends upon the frame bar adjacent said shafts, a pivotal connection between one end of said pivoted bar and the said ear, a pin carried at the upper end of said pivoted bar, a lever having one end pivotally attached to a frame bar of the upper arm sleeve and having notches formed in one side thereof adjacent the other end for the selective engagement of said pin, and a pair of gripping members mounted upon the outer ends of said shafts, said gripping members being shiftable relative to one another through longitudinal actuation of said reciprocable shaft.

7. In a device of the character described, comprising a pair of sleeves, one being designed to receive a handless forearm and the other to receive an upper arm, frame bars extending longitudinally of opposite sides of each of said sleeves, pivotal connecting means between adjacent ends of said frame bars, a shaft mounted upon and extending longitudinally of a frame bar adjacent the forearm sleeve and having one end extended beyond the forward end thereof, said shaft being of substantially semi-circular cross-section from a point adjacent its inner end to its forward end, a reciprocable substantially semi-circular shaft mounted to slide upon the flat portion of the first mentioned shaft, a sleeve surrounding said shaft and having an ear, said sleeve being slidable upon the first mentioned shaft and secured against movement on the reciprocable shaft, a bar pivotally mounted intermediate its ends upon the frame bar adjacent said shaft, a pivotal connection between one end of said pivoted bar and the said ear, a pin carried at the upper end of said pivoted bar, a lever having one end pivotally attached to a frame bar of the 130

upper arm sleeve and having notches formed in one side thereof adjacent the other end for the selective engagement of said pin, a pair of gripping members mounted upon the outer ends of said shafts, said gripping members being shiftable relative to one another through longitudinal actuation of said reciprocable shaft, resilient means normally urging said reciprocable shaft inwardly from the outer end of said forearm sleeve, and resilient means operating to maintain positive engagement between the notched end of said lever and the engaged pin.

8. In a device of the character described, a gripping unit designed to be actuated by a reciprocable shaft, comprising a pair of elongated members each terminating at one end in a laterally directed portion, a pair of bearings at the other end of each of said members, one of said bearings of each member being upon the inside and the other upon the outside thereof, connecting means between the inside bearings of said members, said reciprocable shaft having connection at one end with said connecting means, means for pivotally connecting the other bearings of said members with fixed portions of the device whereby upon reciprocation of said shaft the members will oscillate upon the said other bearings for movement relative to one another, said members being divided transversely to form inner and outer portions, pivotal connecting means between the inner and outer portions of each member, and means for securing the outer portion of each member in a predetermined position relative to the attached inner portion.

9. In a device of the character described including an upper arm receiving sleeve and a sleeve designed to receive a handless forearm, a pivotal connection between said sleeves, a shaft mounted for longitudinal reciprocation at the side of the forearm sleeve, a pair of pivotally connected gripping members mounted at the forward end of the forearm sleeve and having said shaft connected therewith and adapted to effect relative movement between the members when it is reciprocated, a spring member connected with said shaft and normally acting to retract the same, a lever pivotally connected adjacent one end with the upper arm sleeve, means for adjustably connecting the other end of said lever with said shaft, said lever being normally disposed substantially parallel with the shaft, and a spring member connected between the end of said lever adjacent the pivotal point thereof and the upper arm sleeve structure and normally acting to maintain the connection between the other end of the lever and the shaft.

10. In a device of the character described including a sleeve designed to receive an upper arm and a second sleeve designed to receive a handless forearm, a shaft mounted

for longitudinal reciprocation at one side of the forearm receiving sleeve, a pair of pivotally connected gripping members mounted at the forward end of the forearm receiving sleeve, a pivotal connection between the forward end of said shaft and said gripping members, said shaft, when actuated, effecting the relative movement of said gripping members, an ear carried by said shaft, a lever disposed substantially parallel with said shaft, said lever having a notch therein adjacent its forward end, a pin carried by said ear to removably engage in said notch, a pivotal connection between said lever at a point adjacent its other end and the upper arm sleeve, and means for normally holding said pin in engagement in said lever notch.

11. In a device of the character described including a sleeve designed to receive an upper arm and a second sleeve designed to receive a handless forearm, a shaft mounted for longitudinal reciprocation at one side of the forearm receiving sleeve, a pair of pivotally connected gripping members mounted at the forward end of the forearm receiving sleeve, a pivotal connection between the forward end of said shaft and said gripping members, said shaft, when actuated, effecting the relative movement of said gripping members, an ear carried by said shaft, a lever disposed above and normally substantially parallel with said shaft, said lever having a notch therein adjacent its forward end, a pin carried by said ear adapted to receive said notch, a pivotal connection between said lever at a point adjacent its other end and the upper arm sleeve, means for normally holding said pin in engagement in said lever notch, and a spring element connected with said shaft and normally acting to shift the same in one direction.

12. In a device of the character described, an upper arm receiving sleeve, a frame for said sleeve including a pair of bar members extending longitudinally thereof, a sleeve adapted to receive a handless forearm, a frame for said forearm sleeve including a pair of longitudinally extending bars, pivotal connecting means between the upper arm bars and the forearm bars, a pair of bearings carried by and extending laterally from one of said forearm bars, one bearing being at the forward end of the bar and the other being adjacent the rear end thereof, a pair of shafts arranged for relative longitudinal movement, one of said shafts having both ends supported by said bearings, the other shaft extending through the forward bearing only, said shafts having oscillatory movement in the bearings, a pair of pivotally connected gripping members mounted at the forward end of said forearm sleeve, a pivotal connection between the said other one of the shafts and said gripping members whereby upon longitudinal movement of the same

- the gripping members will be moved relative to one another, a lever bar disposed substantially parallel with and above the shafts, a fixed pivotal connection between said lever bar at one end and an upper arm frame bar, means for detachably connecting said lever at its other end with the said other one of the shafts whereby longitudinal movement will be imparted thereto by said lever when the latter is moved, and a spring member having connection at one end with the lever bar adjacent its pivoted end and having its other end adjustably connected with the upper arm frame.
13. In an artificial hand, a hand unit comprising two elongated members each divided transversely to form an inner and outer portion, each of said outer portions having a laterally directed terminal part, a pivotal connection between the inner and outer portions of each of said parts whereby the outer portions may be rotated about an axis extending longitudinally of the member, a pivotal connection between said inner portions whereby the members may be moved relative to one another, means adapted to be mounted upon an arm for actuating said members, and a latching element pivotally mounted upon one of the portions of each member for securing the outer portions in a position of adjustment relative to the inner portions, said outer portions when in one position being adapted to have the ends of the laterally directed parts brought into abutting relation.
14. In an artificial hand, a hand unit comprising two elongated members each divided transversely to form an inner and outer portion, each of said outer portions having a laterally directed terminal part, a pivotal connection between the inner and outer portions of each of said parts whereby the outer portions may be rotated about an axis extending longitudinally of the member, a pivotal connection between said inner portions whereby the members may be moved relative to one another, means adapted to be mounted upon an arm for actuating said members, and a latching element pivotally mounted upon one of the portions of each member for securing the outer portions in a position of adjustment relative to the inner portions, said outer portions when in one position being adapted to have the ends of the laterally directed parts brought into abutting relation, one of said outer portions consisting of a pair of plate members disposed in spaced relation.

In testimony whereof I hereunto affix my signature.

HENRY F. GEISE.
